George D. Richards,
ATTORNEY

UNITED STATES PATENT OFFICE

FREDERICK GOERTZ, OF SOUTH ORANGE, NEW JERSEY, ASSIGNOR TO AUGUST GOERTZ & CO., INC., A CORPORATION OF NEW JERSEY

MEANS FOR DECORATING BOXES

Application filed August 15, 1928. Serial No. 299,694.

This invention relates to improvements in cosmetic boxes or vanity cases; and the invention has for its principal object to provide a simple construction and assembly of 5 parts comprising a body and cover sections hinged together and a novel construction and arrangement of means to mount and retain a design insert upon the cover section of the box or case.

10 Other objects of this invention, not at this time more particularly enumerated, will be fully understood from the following detailed description of the same.

The present invention is clearly illustrated 15 in the accompanying drawings, in which:—

Figure 1 is a top plan view of the box or case closed;

20 Figure 2 is a view similar to Figure 1 and in addition illustrates the method of assembling the design insert with the cover section;

Figure 3 is a central sectional view of the design insert retaining frame shown in elevation;

25 Figure 4 is a view looking at the design insert retaining frame from below;

Figure 5 is a side elevation with parts broken away of the structure shown in Figure 1; and

30 Figure 6 is an enlarged fragmentary view illustrating the method of securing the retaining frame to the cover section.

Similar characters of reference are employed in all of the hereinabove described views, to indicate corresponding parts.

35 Referring now to said drawings, the reference character 10 indicates a body section and 11 a cover section of a cosmetic box or vanity case, said sections being of substantially cylindrical form and hinged together.

40 In boxes or cases of this character, which are designed to serve the purposes of cosmetic carriers or vanity cases, it is usually desired to provide a design in connection with the outer surface of the cover section, and this invention relates to a novel construction of cover section and design insert and a retaining frame for retaining the design insert upon the cover section, said retaining frame being adapted to be firmly and securely assembled 45 with the cover section of the box or case, in

interlocked relation thereto, without necessity of using solder or detachable fastening means of any kind; said retaining frame being adapted to retain the design insert in attached relation to the outer side or face of 55 said cover section 11 and to present a neat and attractive appearance. The outer side or face of said cover section 11 is formed with a circular depression or recess 12 of suitable depth to receive the design insert 13. Recess 12 60 may extend almost to the edges of the outer face of said section, thereby providing an upwardly projecting annular bead 14 extending around the upper periphery of the cover section. The bottom of the recess 12 is provided 65 with a plurality of circumferentially spaced slots 15 at its marginal edges. Four such slots, equally spaced, are illustrated in Figure 2 of the drawings although a greater or lesser number of such slots may be employed. 70

The reference character 16 indicates a retaining frame or annulus having at its inner circumference an incurled annular bead or keeper flange 17 to provide a holding seat for retaining the design insert 13 backed 75 against the bottom of the recess 12 in the cover section. Said retaining frame or annulus 17 has a downwardly extending flange 18 at its outer circumference, which flange is adapted to fit snugly within the recess 12 in the cover 80 section and to surround the peripheral edge of the design insert 13 when the retaining frame is overlaid upon the outside surface of said cover section around the design insert, with the marginal portions of the latter engaged and held by the keeper flange 17. The means for interlocking the retaining frame with the cover section in fixed assembled relation thereto, and in holding engagement 85 with the design insert 13, comprises a plurality of circumferentially spaced downwardly projecting clincher lugs or tongues 20 extending from the flange 18 through the slots 15 in the cover section and bent upon the under or inner side of said cover section as especially illustrated in Figure 6. In assembling the retaining frame with the cover section 11 the extremities of the lugs or tongues 20 are passed through the slots 15 from above 95 the cover section and these lugs are then 100

clinched over in the manner shown in the drawings.

While the retaining flange has been described as a means for retaining a design

5 insert in affixed relation to the outside surface of said cover section, it will be understood that devices other than design inserts such as mirrors may be thus secured upon the cover section.

10 The retaining flange when in assembled relation with the design insert in the recess 12 presents a neat and attractive appearance and has the appearance of being formed integral with the body of the cover section.

15 As many changes could be made in the above construction and many apparently widely different embodiments of this invention could be made without departing from the scope thereof, it is intended that all matter contained in the above description or 20 shown in the accompanying drawings shall be interpreted as illustrative and not in a limiting sense.

What is claimed is:

25 1. In a vanity case having a depression in its outer wall surface and spaced apertures at the margins of said depression, a design insert disposed in said depression, a retaining frame for securing said design insert in place 30 in said depression, said retaining frame having an in-curled head to provide a holding seat for retaining the design insert backed against the bottom of said depression and lugs formed on said retaining frame and extending through said apertures in said section, said lugs being clinched upon the inner surface of said wall.

2. In a vanity case having a depression in its outer wall surface and spaced apertures 40 at the margins of said depression, a design insert disposed in said depression, a retaining frame having a marginal flange surrounding the periphery of said design insert within said depression, said retaining frame acting to secure said design insert in place in said depression and having an in-curled bead to provide a holding seat for retaining the design insert backed against the bottom of said depression, and lugs formed on said 45 marginal flange and extending through said apertures in said wall, said lugs being clinched upon the inner surface of said wall.

50 In testimony, that I claim the invention set forth above I have hereunto set my hand this 55 13th day of August, 1928.

FREDERICK GOERTZ.
